UNITED STATES PATENT OFFICE.

EDWARD P. BULLARD, JR., OF STRATFORD, CONNECTICUT, ASSIGNOR TO THE BULLARD MACHINE TOOL COMPANY, OF BRIDGEPORT, CONNECTICUT, A CORPORATION OF CONNECTICUT.

MULTIPLE-SPINDLE DRILLING MACHINE.

Application filed April 4, 1924. Serial No. 704,096.

This invention relates to a multiple spindle machine tool of the type commercially known as the Bullard Dril-Au-Matic, and particularly a machine tool for drilling, 5 threading or boring operations, and in which the work is secured by means of chucks upon a work table which is intermittently revolved to different work stations, and at which stations individual tool mechanisms 10 operate upon the work; one of the stations, which is a work removing and loading station, being not provided with such tool mechanism.

An object of the invention is to provide a 15 machine of this character in which the indexing mechanism of the work carrier will be co-related with the respective tool mechanisms that the operation of the tools will be synchronized and automatically brought into 20 and out of operative relation with the work.

A further object is to provide a machine in which the stroke, speed and timing of the tools may be adjusted as desired to suit the particular work being done.

25 It is further proposed to provide a novel form of tool mechanism in which the tools will be brought into and out of working relation with the work at relatively great traveling speed, and while in cutting relation with the work itself the traveling speed will be relatively slow.

With the above and other objects in view an embodiment of the invention is shown in the accompanying drawings, and this embodiment will be hereinafter more fully described with reference thereto, and the invention will be finally pointed out in the 35 claims.

In the drawings:

40 Fig. 1 is a vertical sectional view of a multiple spindle machine tool according to the present embodiment of the invention.

Fig. 2 is a horizontal sectional view taken on line 2—2 of Fig. 1 and showing a part of the indexing mechanism in plan;

45 Fig. 3 is a horizontal sectional view taken along line 3—3 of Fig. 1 and also showing a part of the indexing mechanism; and lock pin;

50 Fig. 4 is a horizontal sectional view taken along line 4—4 of Fig. 1 and showing the tripping means for actuating the indexing mechanism;

Fig. 5 is a horizontal sectional view taken

on line 5—5 of Fig. 1 and showing the indexing clutch means;

Fig. 6 is a horizontal sectional view taken along the line 6—6 of Fig. 1;

Fig. 7 is a horizontal sectional plan view taken along line 7—7 of Fig. 1 and showing the several tool feed works, the left hand feed works being along the upper level, the intermediate one being along an intermediate level and the right hand one being along the lower level of said line;

Fig. 8 is a detail vertical sectional view of one of the feed works;

Fig. 9 is a transverse detail vertical sectional view thereof taken on line 9—9 of Fig. 8;

Fig. 10 is a horizontal sectional view taken along line 10—10 of Fig. 8;

Fig. 11 is a diagrammatic perspective view of the main elements of the feed works; and

Figs. 12 to 15 are diagrammatic views of the clutch shifting mechanism employed and respectively showing the same in the several operative positions thereof.

Referring particularly to Fig. 1 of the drawings, the machine comprises a base 20 provided interiorly with a centrally disposed flange 21 upon which a stationary vertically disposed cylindrical column 22 is supported and upon the upper end of which column the housing 23 for the tool mechanism is mounted. Upon the lower portion of the column 22 and within the base 20 there is rotatably mounted a work carrier 24, radially slotted, as at 25 (Fig. 4) to receive suitable supporting chucks for the work, which according to the present embodiment of the machine are placed at four equally spaced stations upon the carrier, the work being intermittently rotated a quarter turn from the loading station, to be brought into successive relation with the several tool mechanisms of the machine, and at the completion of a revolution being brought back to the loading station where it is removed.

The machine is designed to be operated from a continuously driven central shaft 26 disposed vertically within the upper portion of the machine, and adapted to be operated in any suitable manner, as for instance by means of an electric motor geared thereto, or by belting extending over the illustrated pulley 27, geared to the shaft 26 by means of pinions 28 and 29. The shaft 26 operates

both the carrier indexing mechanisms and the tool feed works mechanism.

Upon the shaft 26 there is provided a clutch mechanism indicated generally as 30 and a feed works mechanism driving pinion 31 connected to the clutch, and which are substantially similar in construction and operation to the clutch mechanism shown in U. S. patent to Edward P. Bullard Jr., 10 #1,360,175. The clutch 30 is adapted through co-operation of a cam member 32 mounted upon a central control shaft 33 journaled in suitable bearings 34 and 35 of the housing 23, to intermittently connect 15 and disconnect said driving pinion 31 to the shaft 26, so that the tool feed works are in operation between the indexing periods of the carrier, and out of operation during said periods. The pinion 31 meshes with 20 and operates a large central gear 36 loosely mounted on a standard 37 surrounding the central shaft 33 and which gear is common to and drives the several tool feed works mechanisms. The clutch mechanism 30 is 25 adapted to be manually operated when desired by means of a vertically disposed rotary shaft 38 mounted in the upper portion 23 of the machine and connected by a transverse arm 39 to the clutch, said shaft being 30 further provided with an arm 38^a that is engaged by a pin carried on a slidable annular operating ring 38^b which encircles the upper portion of the machine, so as to control its operation from either side.

35 At the lower end of the shaft 26 there is provided a spiral pinion 40 meshing with a horizontally disposed spiral pinion 41, upon the shaft of which there is provided a worm 42, which meshes with and continuously drives a spiral gear 43 loosely rotatable upon the lower portion 44 of shaft 33 which extends downwardly through the column 22, being journaled in suitable bearings 45 and 46 provided in said column.

45 The machine as designed, in a way constitutes two units or two series of mechanisms, one of which is contained within the upper part of the machine and designed to operate the tool carrying slides, while the 50 other unit is located in the lower part of the machine and constitutes the mechanism for indexing and locking the carrier. The operation of the mechanism contained within the lower unit is in a measure controlled 55 through the connections with and the mechanism comprising the upper unit, and that in turn may be controlled or started and stopped through the manipulation of the manually operable shaft 38 which actuates 60 the clutch mechanism 30 to stop the rotation of the tool driving gear 36.

As before pointed out, the clutch is also operated intermittently by the cam member 32 mounted upon the shaft 33, the clutch 65 having an extended arm 47 provided with

a roll 48 which normally lies in the path of cam portions 49 and 50 upon said cam member and which positively moves the arm up and down to open and close the clutch, one of said cam portions serving to intermittently engage and the other to disengage the clutch. The control shaft 33 is also provided above the cam 32 with a series of three lugs 51 which project radially at different levels, and each being adapted to 70 engage a slide rod 154, hereinafter more fully referred to, of a particular one of the tool feed works mechanisms. The control shaft 33 upon which the cam 32 and the lugs 51 are mounted also supports an indexing controller member 52 mounted near its lower end.

75 Thus the shaft 33 with its cam, lugs and controller member is a single means for controlling the several operations of the 80 machine, as will hereinafter more fully appear.

Upon the lower portion of the shaft 44 is mounted a gear 53 that meshes with and drives another gear 54 mounted upon a crank shaft 55 journaled in bearings 56 formed upon the inside of the column 22, said shaft carrying upon its lower end a crank 57 connected to an indexing arm 58, having a straight guide-way 59 formed in its upper face to engage and disengage the several indexing rollers 60 of the carrier to index it, there being four such equally spaced rollers in the present embodiment of the 100 invention. In operation the arm 58 is given an oscillatory movement by reason of its being connected by the crank 57, carried upon the end of the rotatable crank shaft 55, and slidably connected to a shoe 61, 105 rotatably mounted in a cylindrical bearing portion 62, formed in the lower end of the column 22 directly below and in axial alignment with the shaft 44; so that, with each operation of the arm 58 one of the rollers 60 is engaged and the carrier 24 is rotated through a quarter of the revolution, thus moving the work chucks secured upon the table portion of the carrier from one operating station to another. The carrier 24 is rotatably supported upon suitable thrust bearings 63 at the lower end of the column 22, and its upper end is disposed beneath the flange 64 of the said column.

110 In order to properly hold the carrier in position between the indexing periods and during the operation of the tools, and to effect a quick release of the same when the work upon the carrier has been completed, there is provided a mechanism shown in 115 Figs. 1 and 3 wherein it will be seen that there is mounted upon the shaft 44 a cam 65 against which bears a roll 66 mounted upon the outer end of a rocker arm 67 pivoted at 68. This arm carries upper and lower shoes 69 that slidably operate in a 120 125 130

groove of a collar 70 mounted upon the reduced end 71 of a lock pin 72, said lock pin being slidably mounted in a bearing 73 of the column 22. A spring 74 is in position 5 between the collar upon the reduced end of the lock pin and the shoulder of the same pin, so as to normally tend to hold the lock pin to its seat. There is but one movable pin 72 mounted in the column, whereas there 10 are four stationary lock pins 75 mounted in the carrier, and positioned at equal distances apart for engagement by the lock pin 72 when the carrier is in position to co-operate with the tools. It is apparent that with each 15 turn of the shaft 44 and each quarter turn of the carrier the cam 65 will make a complete rotation and serves to withdraw the lock pin 72 from one of the fixed lock pins 75 and reseat it against the next fixed lock 20 pin which is brought into position to lock therewith.

In order to insure a more accurate positioning of the carrier with each stopping of the same, there is provided, in addition to 25 the above described lock pin mechanism, a binding device, which is positioned about one-third of the distance around the column, to effect an engagement with the carrier simultaneously with that of the lock pin, so 30 as to positively insure the accurate positioning of the carrier with each setting of the same, and to prevent its possible displacement due to the cutting pressure of the tools. This mechanism includes a lever 76 which is 35 pivoted at 77 to the column and is provided with an adjustable yieldably mounted screw 78 that contacts with a lug 79 formed upon the under side of the cam 65. A plug 80 is slidably fitted in a radial hole formed in the 40 face of the cylindrical portion of the column 22 in position to engage the inner wall of the carrier and upon the arm 76 is provided an adjustable member 81 to engage the inner 45 end of the plug 80 so that with each rotation of the cam 65, and the positioning of the same as in Fig. 3, to effect the locking of the carrier to the column, the lug 79 of the cam will be brought to register with the screw 78 of the arm 76, so as to throw the same out 50 and in turn force the plug tightly against the wall of the carrier, and thereby causing engagement at that point, as well as at the point engaged by the locking pin 72.

The matter of the releasing, starting and 55 indexing of the carrier, as well as the binding and locking of the carrier when again positioned, is controlled by a single unit situated within the upper portion of the column and mounted upon the central shaft 44, 60 which unit is in turn released by the operation of the tool slides and particularly by the last slide up in the operation of the machine; that is, when the slides are so arranged that they do not all move alike.

65 The indexing mechanism as shown in

Figs. 1, 4, 5 and 6 comprises in part the above mentioned controller member 52 which includes a series of four equally spaced radial studs 82 formed upon its face at different levels, and adapted to be engaged by a like number of releasing and locking pins 83 mounted in the column, three of which are adapted to be actuated by the three tool slides 84 mounted for vertically reciprocation upon the column in slide ways 70 85, while the other one, provided at the forward loading and unloading station, is provided with a handle 86 for manually moving it into and out of relation with its respective stud 82, this fourth releasing and locking pin being normally out of engagement with the controller member during the operation of the machine.

The three releasing and locking pins operable by the tool slides are normally pressed 85 into engagement with the controller member in abutting and locking relation to the studs 82 by means of springs 87, and are each provided at their outwardly projecting ends with a cam surface 88 adapted as the slides 90 reach their uppermost position to be engaged by a camming portion 89 upon each slide to draw the pins outwardly, thereby releasing the controller member. Inasmuch as each pin 83 functions to independently lock 95 the controller the latter will only be released after the last slide is fully up.

Upon release the controller is free to be actuated by means of a spring 90, one end of which is secured to a pin carried by the 100 controller (Fig. 3) and the other end to an arm 91 (Fig. 5) keyed to the shaft 44. The action of this spring upon the controller member is merely to impart to it a slight preliminary rotary movement sufficient to 105 lock the continuously driven gear 43 to the shaft 44.

The locking means employed includes a bell crank lever 92 which is pivotally mounted upon the arm 91, the longer arm of the bell crank having a pin 93 that is disposed upward and engages a socket 94 formed in a plate attached to the under side of the controller member, so that the above mentioned rotary movement of said member imparted 110 by the action of the spring will tend to swing the bell crank lever upon its pivot. The short arm of the bell crank also carries a pin 95, that engages a cross slot in a lock pin 96 slidably mounted in a guide way 115 formed in the arm 91. The outer end portion of this lock pin is positioned to engage the notches 97 in the clutch face 98 of the gear 43, said gear being loose upon the shaft 44, so that upon engagement of the lock pin 120 therewith said shaft is rotated through the keyed connection of the arm 91 thereto to index the carrier.

It is obvious that the controller member 52 is also rotated with the clutch face 98 of 125

the gear 43, and that the shaft 33 turns with it causing the cam 32 to operate the clutch 30 and the lugs 51 to engage the tool mechanism just prior to the completion of the single revolution. As soon as the feed works mechanism starts to operate upon engagement of the lugs 51 therewith, and which mechanism and operation will be presently fully described, the tool slides 84 start to move downwardly toward the work carrier, the first one starting releasing its lock pin 83 so that said pin moves into the path of its respective lug 82 upon the controller member 52, and thereby stops the rotation of said member at the completion of a single revolution. When this occurs the continued rotation of the gear 43 and the arm 91 tensions the spring 90, to impart the next starting impulse to the controller upon release, and the bell crank lever 92 is rocked to withdraw the locking pin 96 from the clutch face 98 of said gear 43, thereby stopping the rotation of the carrier indexing shaft 44.

As before mentioned, the machine includes a series of three tool carrying slides for operating in conjunction with work chucks upon the work table of the carrier, and these are each operated through a separate set of feed works arranged in the upper portion 23 of the machine, and positioned around the large gear 36, which is common to the several feed works and through which they are driven. These several feed works are alike in construction and operation, and therefore a detail description of one set will be sufficient as applying to the others. The feed works serves to move the tool carrying slides 84 up and down and also to rotate the tool drill 99 provided in each slide. It will be understood that other forms of tools, than drills, and reamers may be provided upon the tool slide, depending upon the particular character of the work to be done.

The feed works includes a frame 100 of special form mounted in the housing 23 and the upper end of which the upper bearing 34 of the controller shaft 33 is bolted as shown in Figs. 1 and 8. Within this frame there is journaled a vertical driving shaft 101 provided at its lower end with a gear 102 meshing with and driven by the common driving gear 36, which as before pointed out is driven by the continuously driven shaft 26.

At the upper end of the shaft 101 there is provided a gear 103 meshing with and driving a gear 104 provided at the upper end of a vertical shaft 105 also journaled in the frame 100, the shaft 101 adapted to drive a quick operating mechanism to bring the tool slide into and out of working relation, while the shaft 105 drives a slow feed for lowering the tool slide while the tool is in actual working relation with the work, these

feeds being clutched into operative relation by mechanism presently to be described.

The frame 100 is provided at each side with vertical slide ways 106 and 107 in which a vertically slidable cross head 108 having an inclined slot 109 therein is mounted, and which is provided centrally with a downwardly extending rack 110 connected at its lower end, as at 111 (Fig. 1), to a vertical rod 112 secured to and supporting the tool slide 84, so that upon raising and lowering movement of the cross head the tool slide is also raised and lowered. A vertically movable counterweight 84^a is connected to the tool slide 84 by a chain 84^b passing over suitably arranged pulleys 84^c.

The drill 99 of the tool slide is provided with an upwardly extending shaft 113, slidably keyed at its upper end in a driving sleeve 114 rotatably mounted in bearings 115 of the frame 100, and provided at its upper end with a large gear 116 meshing with another large gear 117, provided upon a stud shaft 118 secured to and depending from the upper side of the housing 23. A gear 119 is fixed to the under side of the gear 117 and meshes with a pinion 120 at the upper end of the shaft 101, this train of gears being adapted to rotate the drill 99 as it is raised and lowered.

A horizontal shaft 121 is journaled in a bearing 122 in the frame 100 and has keyed thereto a crank disk 123, carrying a roller 124 which engages the slot 109 of the cross head 108, and is adapted through rotation of the crank disk to raise and lower said cross head. A sliding clutch collar 125 is keyed to the shaft 120, being provided upon its inner face with clutch teeth 126, and upon the inner end of the shaft there is loosely rotatable a clutch sleeve 127, having clutch teeth adapted to be engaged by the clutch teeth 126, and provided with a worm gear 128 meshing with and driven by a worm 129 provided upon the shaft 101. The sleeve 127 is journaled in a forked bearing portion 130 of the frame. When the clutch teeth 126 are engaged with the clutch sleeve 127 (Fig. 8) the crank disk is rotated with relative rapidity to impart a rapid movement to the cross head 108.

The slow feed mechanism consists of a spur gear 131 meshing with the rack 110 of the cross head, being keyed upon a horizontal shaft 132 journaled in suitable bearings 133 of the frame, and provided at its outer end with a larger spur gear 134 meshing with a spur gear 135 mounted upon a horizontal shaft 136 journaled in suitable bearing portions 137 of the frame. The horizontal shaft 136 is provided with a sliding clutch collar 138 keyed thereto, and having inclined ratchet clutch teeth 139 at its inner face. A clutch sleeve 140 also having

inclined ratchet clutch teeth is loosely mounted on the shaft 132 in a suitable bearing portion 141 of the frame, and is adapted to be engaged by the clutch teeth 139, said clutch sleeve being provided with a worm gear 142 meshing with and driven by a worm 143 provided upon a horizontal shaft 144 journaled in bearings 145 of the frame, said shaft being provided at its end with a worm gear 146 meshing with a worm 147 provided on the shaft 105. When the clutch teeth 139 are engaged with the clutch sleeve 140, the rapid feed clutch collar 125 being at the same time disengaged, slow downward feeding movement is imparted to the cross head through the rotation of the pinion 131. It is obvious that when the upper rapid motion clutch is engaged and the lower slow feed clutch disengaged, that a rapid downward movement will be imparted to the tool slide; and that when the lower slow feed clutch is engaged and the upper rapid feed clutch is disengaged, slow downward feeding movement will be imparted to the slide; and further that when both clutches are disengaged, or in the neutral position, the feeding movement of the tool slide is stopped. According to the present invention the rapid downward movement takes place from the uppermost position of the tool slide to an adjustable point calculated as being just prior to engagement of the tool with the work, the slow downward feed taking place from this point to the lowermost position of the tool slide. In this lowermost position a slight dwell occurs, during which the slide is motionless, and thereupon it moves to the uppermost position through the operation of the rapid feed mechanism, mechanism presently to be referred to being brought into operation at the completion of the upward feed to move the clutches into neutral position. When in this neutral position the indexing mechanism operates. As before pointed out the tool feed works mechanism is again brought into operation at the completion of the indexing operation through engagement of the lugs 51 of the shaft 33 with the feed works.

Upon a suitable bearing portion 148 of the frame 100 there is pivotally mounted a clutch shifting lever arm 149 provided at its upper and lower ends with projecting lugs 150 and 151 respectively engaged with the upper and lower clutch collars 125 and 138 and also provided in its upper end with a spring pressed pointed plunger 152 disposed in a barrel portion 153 of said lever, and adapted to co-operate with a horizontally disposed control slide 154 mounted in bearing portions 155 and 156 of the frame. This slide is provided intermediate its ends with a knife edge camming member 157, engaged by the plunger 152, and at its inner end is provided with a pin 158 adapted to be engaged with the respective actuating lug 51 mounted on the shaft 33, and at its outer end is provided with a lug 159 adapted to be engaged by stop means, presently to be described, mounted upon the crank disk 123.

Adjustable stops 157^a and 157^b are provided on the bearings 155 and 156 to abut the member 157 and thereby limit the movements of the slide 154 in either direction. It will be understood that the relation of the plunger end 152 of the clutch actuating lever and the knife edge cam 157 is such that upon the sliding movement of the slide 154 the plunger will be depressed without swinging the lever until the point of the cam 157 is passed whereupon the lever will be thrown in either direction, depending upon the direction in which the slide is moved, with a quick snap action. As shown in Fig. 12, the slide has been moved to the left through engagement of the actuating lug 51 therewith and the clutch operating lever upon passing the point of the cam 157 has been moved to its extreme position in clockwise direction, engaging the rapid feed clutch 125 and disengaging the slow feed clutch 138. The crank disk is therefore rapidly rotated to lower the cross head of the tool slide, this operation continuing until the stop member 160 mounted within a concentric slot 161 of the crank disk engages the lug 159 at the forward end of the slide 154, thereby moving it inwardly to a point at which the cam 157 passes the point of the plunger 152 and the clutch actuating lever is swung in counterclockwise direction to the position indicated in Fig. 13 and in which position the upper rapid movement clutch 125 is disengaged and the lower slow movement clutch 138 is engaged, so that the pinion 131 is caused to rotate, and slowly moves the cross-head downwardly to its extreme lowered position, the rotating drill 99 being in engagement with the work during this slow feed.

The stop member 160 is adjustably mounted in the slot 161 by means of a clamping plate 162, which plate is provided with an indexing point 163 disposed in relation to a series of indexing marks 164 upon the face of the crank disk, the adjusted position of this stop 160 determining the point in the downward movement of the cross head at which the rapid feed is thrown out and the slow feed is thrown in. As the cross head reaches its lowermost position an adjustable pin 165 provided thereon engages the outer arm of a bell crank lever 166 pivoted at 167 upon the frame 100 and having its lower end engaged with the lower end of a vertically disposed push rod 168 slidable in bearing portions 169 of the frame. At its upper end the push rod is provided with an inclined cam surface 170 adapted to engage the inclined end wall 171 of a cut-out 172

provided in the slide 154 to move said slide to the left as indicated in full lines in Fig. 14. This movement of the slide is not sufficient to bring the point of the cam 157 past the point of the plunger 152 but brings said points to within about one-eighth of an inch of each other. In this position the slow feed clutch is still engaged, but the tool slide has reached its lowermost position by reason of the fact that an adjustable stop 178 (Fig. 1) provided upon the slide has engaged the flange 64 of the column 22 so that further downward movement of the slide is not possible. The clutch collar 138 is therefore held against further rotary movement, while the clutch sleeve 140 continues to rotate. This condition causes the inclined ratchet teeth of the sleeve 140 to force the clutch collar to the left and which movement is sufficient to move the end of the plunger 152 past the point 157, whereupon the lower slow feed clutch is thrown out and the upper rapid feed clutch is thrown in, as shown in dotted lines in Fig. 14, and the tool slide is rapidly moved to its uppermost position. It will thus be seen that in the lowermost position of the tool slide there is a short period or dwell during which there is neither up or down movement of the slide and after this stationary period the slide moves upwardly.

As the slide reaches its uppermost position a stop member 174 upon the crank disk engages the lug 159 of the slide 154, moving it to a position to swing the lever 149 to disengage the rapid feed clutch. As the lever is moved by engagement of the stop 174 with the lug 159 a projecting neutralizing pin 175 upon the crank disk engages a slide pin 176 mounted in the bearing portion 122 of the frame 100 moving said pin inwardly as indicated in Fig. 15, so that as the clutch column 125 is disengaged from the clutch sleeve it abuts the slide pin 176 thereby preventing complete counterclockwise movement of the lever 149, so that the lower or slow feed clutch 138 is prevented from engaging the sleeve 140, and the clutches are thereby both placed in neutral position and the feeding of the cross arm and tool slide is stopped, being again started after the indexing of the carrier by engagement of the lug 51 with the pin 158 of the slide 154, as before pointed out.

In order to manually adjust the position of the crank disk to raise or lower the tool slide the same is provided in its periphery with spiral worm teeth 177 engaged by a worm 178 journaled in bearings 179 of the frame and provided at the lower end of its shaft with a clutch face 180.

In normally spaced relation below the clutch face 180 a clutch face 181 is arranged upon the upper end of a shaft 182 mounted for vertical movement in a bearing 183.

Upon this shaft there is provided a grooved collar 184 having an upper cone portion above which is disposed the forked arm 185 of a vertical clutch-neutralizing shaft 186 journaled in a bearing 187 of the frame, said shaft being provided at its upper end with a roller arm 188 engaging the clutch collar 138, and having a manually operable crank handle 189 at its lower end. The collar 184 is engaged at one end by a lever 190, pivoted upon the frame 100 at 191, and engaged at its other end in the upper grooved end of a vertically movable shaft 192, journaled in a bearing 193, and provided at its lower end with a manually operable crank handle 194. The shaft 192 is furthermore provided with a sprocket gear 195 connected by a sprocket chain 196 with a sprocket gear 197 provided on the lower end of the shaft 182. In order to adjust the tool slide the crank handle 194 is drawn downwardly to the dotted line position (Fig. 8), causing the lever 190 to be turned to raise the shaft 182 to engage the clutch 181 with the clutch 180. At the same time the cone surface of the collar 184 engages between the forked arm 185 rotating the shaft 186 to a neutral position, that is a position in which the clutches 125 and 138 are both disengaged from their respective driving means, so that the tool slide is free to be manually adjusted. Thereupon the crank handle 194 is turned, and through the sprocket chain 196 the shaft 182 is rotated to impart rotation to the worm 178, thereby rotating the crank disk to adjust the position of the tool slide. It is obvious that the handle 189 may be turned independently of the tool slide adjusting means to engage either of the clutches 125 or 138, or to move them into neutral position.

I have illustrated and described a preferred and satisfactory embodiment of the invention but it will be obvious that changes may be made therein within the spirit and scope thereof as defined in the appended claims.

Having thus described my invention, what I claim and desire to secure by Letters Patent is:

1. In an automatic machine tool of the character described, a work support, a tool slide, rotary feed means having movement in one direction connected to said tool slide and adapted to move said slide in a given point in relation to the work at one speed, other feed means adapted to move said slide to a given point in relation to the work at a different speed, said tool slide adapted by said secondary movement to move said first means with it during the movement to the limit of its traverse, said first feed means adapted to move said slide in return direction out of relation with the work at relatively rapid speed.

2. In an automatic machine tool of the character described, a work support, a reciprocating tool slide, rotary feed means having movement in one direction and connected to said tool slide to feed it toward and away from said work support at a given speed, and other feed means connected to said slide adapted during a given period in the rotation of said first feed means to impart secondary movement to said slide at a different speed from the speed imparted by said first feed means.

3. In an automatic machine tool of the character described, a work support, a reciprocating tool slide, rotary feed means having movement in one direction and eccentrically connected to said tool slide to feed it toward and away from said work support at a given speed and other feed means connected to said slide adapted during a given period in the rotation of said first feed means to impart secondary movement to said slide at a different speed from the speed imparted by said first feed means.

4. In an automatic machine tool of the character described, a work support, a reciprocating tool slide, rotary feed means having movement in one direction and connected to said tool slide to feed it toward and away from said work support at relatively rapid speed and other feed means connected to said slide adapted during a given period in the rotation of said first feed means to impart secondary movement to said slide at relatively slow speed.

5. In an automatic machine tool of the character described, a work support, a reciprocating tool slide, rotary feed means connected to said slide to feed it toward and away from said work support at a given speed, drive means therefore adapted to drive said feed means in one direction, a clutch for said drive means, other feed means connected to said slide, drive means therefore adapted to drive said other feed means in one direction at a different speed from said first feed means, a clutch for said second drive means, clutch shifting means connected to said clutches whereby as one is connected the other is disconnected, and means carried by said first feed means adapted to actuate said shifting means at a predetermined point in the movement of said slide toward the work to connect said other feed means.

6. In an automatic machine tool of the character described, a work support, a reciprocating tool slide, rotary feed means connected to said slide to feed it toward and away from said work support at a given speed, drive means therefore adapted to drive said feed means in one direction, a clutch for said drive means, other feed means connected to said slide, drive means

therefore adapted to drive said other feed means in one direction at a different speed from said first feed means, a clutch for said second drive means, clutch shifting means connected to said clutches whereby as one is connected the other is disconnected, and adjustable means carried by said first feed means adapted to actuate said shifting means at a predetermined point in the movement of said slide toward the work to connect said other feed means.

7. In an automatic machine tool of the character described, a work support, a reciprocating tool slide, rotary feed means connected to said slide, to feed it toward and away from said work support at a given speed, drive means therefore adapted to drive said feed means in one direction, a clutch for said drive means, other feed means connected to said slide, drive means therefore adapted to drive said other feed means in one direction at a different speed from said first feed means, a clutch for said second drive means, clutch shifting means connected to clutches whereby as one is connected the other is disconnected, and means actuated at the end of the movement of said slide toward the work adapted to actuate said clutch shifting means to connect said first drive means.

8. In an automatic machine tool of the character described, a work support, a reciprocating tool slide, rotary feed means connected to said slide to feed it toward and away from said work at a given speed, drive means therefore adapted to drive said feed means in one direction, a clutch for said drive means, other feed means connected to said slide, drive means therefore, adapted to drive said other feed means in one direction at a different speed from said first feed means, a clutch for said second drive means, clutch shifting means connected to said clutches whereby as one is connected the other is disconnected, means actuated at the end of the movement of said slide toward the work adapted to actuate said clutch shifting means to connect said first driving means to effect return movement of the slide and means carried by said first feed means adapted to actuate said shifting means to neutral position at the end of the return movement of the slide whereby both clutches are disengaged.

9. In an automatic machine tool of the character described, a work support, a tool slide, variable speed feed means adapted to move said slide in working relation with the work at a given speed, and to move it in return direction out of relation with the work at relatively different speed, stop means for said slide adapted to limit its movement toward the work, and a yieldable connection between said feed means and said

- slide whereby said slide remains stationary for a relatively short period before said return feed movement.
10. In an automatic machine tool of the character described, a work support, a tool slide, variable speed feed means adapted to move said slide to a given point in relation to the work at one speed and to the limit of its traverse at a different speed, and to move said slide in return direction out of relation with the work at relative rapid speed, stop means for said slide adapted to limit its movement toward the work, and a yieldable connection between said feed means and said slide whereby said slide remains stationary for a relatively short period before said return feed movement.
11. In an automatic machine tool of the character described, a work support, a tool slide, variable speed feed means adapted to move said slide to a given point in relation to the work at relatively rapid speed and to the limit of its traverse at relatively slow speed, and to move said slide in return direction out of relation with the work at relatively rapid speed, stop means for said slide adapted to limit its movement toward the work, and a yieldable connection between said feed means and said slide whereby said slide remains stationary for a relatively short period before said return feed movement.
12. In an automatic machine tool of the character described, a work support, a tool slide, feed means adapted to move said slide to a given point in relation to the work at one speed, other feed means adapted to move said slide to the limit of its traverse at a different speed, said first feed means adapted to move said slide in return direction out of relation with the work at constant speed, means adapted to be actuated at the end of said return movement to stop the operation of said feed means, and means adapted to be set in operation upon stopping of said feed means to start said feed means at the end of a given period.
13. In an automatic machine tool of the character described, a work support, a tool slide, feed means adapted to move said slide to a given point in relation to the work at one speed, other feed means adapted to move said slide and to the limit of its traverse at a different speed, said first feed means adapted to move said slide in return direction out of relation with the work at constant speed, and means actuated by said slide adapted to stop the operation of said feed means and to start it after a given period.
14. In an automatic machine tool of the character described, a work support, a reciprocating tool slide, independent different speed drive means geared to said slide, one of said drive means being continuously rotatable in one direction during the feed of the slide and adapted to impart initial feed and complete return movement thereto, and means for operatively connecting one and disconnecting the other at a predetermined point in the feed of the slide.
15. In an automatic machine tool of the character described, a work support, a tool slide, rapid and slow feed means independently geared to said slide, driving means for driving said feed means respectively in one direction, clutch means for connecting said respective drive means to said respective feed means, and control means adapted to engage one of said clutch means and disengage the other at predetermined points in the movement of the slide.
16. In an automatic machine tool of the character described, a work support, a tool slide, rapid and slow feed means independently geared to said slide, driving means for driving said feed means respectively in one direction, clutch means for connecting said respective drive means to said respective feed means, control means adapted to be primarily actuated to engage said rapid feed clutch means, means adapted to actuate said control means at a predetermined point in the feeding movement of said slide to disengage said rapid feed clutch means and engage said slow feed clutch means, and means adapted at the end of the feeding movement of said slide to disengage said slow feed clutch means and engage said rapid feed clutch means to effect rapid return movement of said slide.
17. In an automatic machine tool of the character described, a work support, a tool slide, rapid and slow feed means independently geared to said slide, driving means for driving said feed means respectively in one direction, clutch means for connecting said respective drive means to said respective feed means, control means adapted to be primarily actuated to engage said rapid feed clutch means, adjustable means adapted to actuate said control means at a predetermined point in the feeding movement of said slide to disengage said rapid feed clutch means and engage said slow feed clutch means, and means adapted at the end of the feeding movement of said slide to disengage said slow feed clutch means and engage said rapid feed clutch means to effect rapid return movement of said slide.
18. In an automatic machine tool of the character described, a work support, a tool slide, rapid and slow feed means independently geared to said slide, driving means for driving said feed means respectively in one direction, clutch means for connecting said respective drive means to said respective feed means, control means adapted to be primarily actuated to engage said rapid feed clutch means, means adapted to actuate said control means at a predetermined point in

- the feeding movement of said slide to disengage said rapid feed clutch means and engage said slow feed clutch means, means adapted to stop the feed of said slide at the 5 end of said slow feed for a predetermined period, and means adapted at the end of said period to engage said rapid feed clutch means to effect rapid return of said slide. 70
19. In an automatic machine tool of the 10 character described, a work support, a tool slide, rapid and slow feed means independently geared to said slide, driving means for driving said feed means respectively in one direction, clutch means for connecting said 15 respective drive means to said respective feed means, control means adapted to be primarily actuated to engage said rapid feed clutch means, means adapted to actuate said control means at a predetermined point in the feeding 20 movement of said slide to disengage said rapid feed clutch means and engage said slow feed clutch means, means adapted at the end of the feeding movement of said slide to disengage said slow feed clutch means 25 and engage said rapid feed clutch means to effect rapid return movement of said slide, and means adapted at the end of said rapid return movement to move said rapid and slow feed clutch means into neutral position. 30
20. In an automatic machine tool of the character described, a work support, a tool slide, rapid and slow feed means independently geared to said slide, driving means for driving said feed means respectively in one 35 direction, clutch means for connecting said respective drive means to said respective feed means, control means adapted to be primarily actuated to engage said rapid feed clutch means, means adapted to actuate said 40 control means at a predetermined point in the feeding movement of said slide to disengage said rapid feed clutch means and engage said slow feed clutch means, means adapted at the end of the feeding movement 45 of said slide to disengage said slow feed clutch means and engage said rapid feed clutch means to effect rapid return movement of said slide, means adapted at the end of said return movement to move said rapid 50 and slow feed clutch means into neutral position, and means actuated by said slide adapted at the end of a predetermined period to actuate said control means to primarily engage said rapid feed clutch means. 55
21. In an automatic machine tool of the character described, a work support, a tool slide, a cross head connected to said tool slide including a vertical rack, rotatable crank means connected to said cross head to reciprocate it, a driving gear engaging said rack to reciprocate it at different speed and independently from said crank means, means for driving said crank means, means for driving said gear, clutch means for connecting said crank means and its driving means, 60
- clutch means for connecting said gear and its driving means, clutch shifting means adapted to engage one of said clutch means and disengage the other, and control means adapted to be actuated at predetermined point to operate said clutch shifting means to effect variable feed of said slide. 70
22. In an automatic machine tool of the character described, a work support, a tool slide, a cross head connected to said slide having a transverse slot and a vertical rack, rotatable crank means engaging said slot and adapted to reciprocate said cross head, a driving gear engaging said rack to reciprocate it at different speed and independently from said crank means, means for driving said crank means, means for driving said gear, clutch means for connecting said crank means to its driving means, clutch means for connecting said gear and its driving means, 75 clutch shifting means adapted to engage one of said clutch means and disengage the other, and control means adapted to be actuated at predetermined points to operate said clutch shifting means to effect variable feed of said slide. 80
23. In an automatic machine tool of the character described, a work support, a tool slide, feed means having an eccentric connection with said tool slide adapted during rotation in one direction to effect feed and return movement of the slide, other feed means connected to said slide adapted to feed it at a different speed from the normal speed of said first feed means, independent drive means for both said feed means for driving them respectively in one direction, clutch means for connecting said feed means to their respective drive means, clutch shifting means adapted to engage one of said clutch means and disengage the other, control means for said clutch shifting means, and means on said first feed means adapted at a predetermined point to actuate said control means to disengage the clutch means of said first feed means and engage the clutch means of said other feed means. 95
24. In an automatic machine tool of the character described, a work support, a tool slide, feed means having an eccentric connection with said tool slide adapted during rotation in one direction to effect feed and return movement of the slide, other feed means connected to said slide adapted to feed it at a different speed from the normal speed of said first feed means, independent drive means for both said feed means for driving them respectively in one direction, clutch means for connecting said feed means to their respective drive means, clutch shifting means adapted to engage one of said clutch means and disengage the other, control means for said clutch shifting means, and adjustable means on said first feed means adapted at a predetermined point to actuate said control 100
- means to disengage the clutch means of said first feed means and engage the clutch means of said other feed means. 105
25. In an automatic machine tool of the character described, a work support, a tool slide, feed means having an eccentric connection with said tool slide adapted during rotation in one direction to effect feed and return movement of the slide, other feed means connected to said slide adapted to feed it at a different speed from the normal speed of said first feed means, independent drive means for both said feed means for driving them respectively in one direction, clutch means for connecting said feed means to their respective drive means, clutch shifting means adapted to engage one of said clutch means and disengage the other, control means for said clutch shifting means, and adjustable means on said first feed means adapted at a predetermined point to actuate said control 110
- means to disengage the clutch means of said first feed means and engage the clutch means of said other feed means. 115
26. In an automatic machine tool of the character described, a work support, a tool slide, feed means having an eccentric connection with said tool slide adapted during rotation in one direction to effect feed and return movement of the slide, other feed means connected to said slide adapted to feed it at a different speed from the normal speed of said first feed means, independent drive means for both said feed means for driving them respectively in one direction, clutch means for connecting said feed means to their respective drive means, clutch shifting means adapted to engage one of said clutch means and disengage the other, control means for said clutch shifting means, and adjustable means on said first feed means adapted at a predetermined point to actuate said control 120
- means to disengage the clutch means of said first feed means and engage the clutch means of said other feed means. 125
27. In an automatic machine tool of the character described, a work support, a tool slide, feed means having an eccentric connection with said tool slide adapted during rotation in one direction to effect feed and return movement of the slide, other feed means connected to said slide adapted to feed it at a different speed from the normal speed of said first feed means, independent drive means for both said feed means for driving them respectively in one direction, clutch means for connecting said feed means to their respective drive means, clutch shifting means adapted to engage one of said clutch means and disengage the other, control means for said clutch shifting means, and adjustable means on said first feed means adapted at a predetermined point to actuate said control 130

means to disengage the clutch means of said first feed means and engage the clutch means of said other feed means.

25. In an automatic machine tool of the character described, a work support, a tool slide, feed means having an eccentric connection with said tool slide adapted during rotation in one direction to effect feed and return movement of the slide, other feed means connected to said slide adapted to feed it at a different speed from the normal speed of said first feed means, independent drive means for both said feed means for driving them respectively in one direction, clutch means 10 for connecting said feed means to their respective drive means, clutch shifting means adapted to engage one of said clutch means and disengage the other, control means for said clutch shifting means, means on said 15 first feed means adapted at a predetermined point to actuate said control means to disengage the clutch means of said first feed means and engage the clutch means of said other feed means, and means adapted to be 20 actuated at the completion of the forward feed of the slide to operate said control means whereby said clutch shifting means is actuated to disengage said clutch means of said other feed means and engage said clutch 25 means of said first feed means, whereby return movement of said slide is effected by said first feed means.

26. In an automatic machine tool of the character described, a work support, a tool slide, feed means having an eccentric connection with said tool slide adapted during rotation in one direction to effect feed and return movement of the slide, other feed means connected to said slide adapted to feed it at a different speed from the normal speed of said first feed means, independent drive means for both said feed means for driving them respectively in one direction, clutch means for connecting said feed means to 35 their respective drive means, clutch shifting means adapted to engage one of said clutch means and disengage the other, control means for said clutch shifting means, means on said first feed means adapted at a predetermined point to actuate said control means to disengage the clutch means of said first feed means and engage the clutch means of said other feed means, means adapted to be 40 actuated at the completion of the forward feed of the slide to operate said control means whereby said clutch shifting means is actuated to disengage said clutch means of said other feed means and engage said clutch 45 means of said first feed means, whereby return movement of said slide is effected by said first feed means, and means on said first feed means adapted at the end of said return movement to actuate said control means to disengage said clutch means of said first feed means.

27. In an automatic machine tool of the character described, a work support, a tool slide, feed means having an eccentric connection with said tool slide adapted during rotation in one direction to effect feed and return movement of the slide, other feed means connected to said slide adapted to feed it at a different speed from the normal speed of said first feed means, independent drive means for both said feed means for driving them respectively in one direction, clutch means for connecting said feed means to their respective drive means, clutch shifting means adapted to engage one of said clutch means and disengage the other, control means for said clutch shifting means, means on said first feed means adapted at a predetermined point to actuate said control means to disengage the clutch means of said first feed means and engage the clutch means of said other feed means, means adapted to be actuated at the completion of the forward feed of the slide to operate said control means whereby said clutch shifting means is actuated to disengage said clutch means of said other feed means and engage said clutch means of said first feed means, whereby return movement of said slide is effected by said first feed means, means on said first feed means adapted at the end of said return feed movement to move both of said clutch means into neutral position.

28. In an automatic machine tool of the character described, a work support, a tool slide, feed means having an eccentric connection with said tool slide adapted during rotation in one direction to effect feed and return movement of the slide, other feed means connected to said slide adapted to feed it at a different speed from the normal speed of said first feed means, independent drive means for both said feed means for driving them respectively in one direction, clutch means for connecting said feed means to their respective drive means, clutch shifting means adapted to engage one of said clutch means and disengage the other, control means for said clutch shifting means, means on said first feed means adapted at a predetermined point to actuate said control means to disengage the clutch means of said first feed means, and engage the clutch means of said other feed means, means adapted to be actuated at the completion of the forward feed of the slide to operate said control means whereby said clutch shifting means is actuated to disengage said clutch means of said other feed means and engage said clutch means of said first feed means, whereby return movement of said slide is effected by said first feed means, means on said first feed means adapted at the end of said return movement to actuate said control means to disengage said clutch means of said first feed means, and neutralizing means adapted 100

to be actuated by said first feed means to maintain both of said clutch means in neutral position.

29. In an automatic machine tool of the character described, a work support, a tool slide, feed means having an eccentric connection with said tool slide adapted during rotation in one direction to effect feed and return movement of the slide, other feed means connected to said slide adapted to feed it at a different speed from the normal speed of said first feed means, independent drive means for both said feed means for driving them respectively in one direction, clutch means for connecting said feed means to their respective drive means, clutch shifting means adapted to engage one of said clutch means and disengage the other, control means for said clutch shifting means, means on said first feed means adapted at a predetermined point to actuate said control means to disengage the clutch means of said first feed means and engage the clutch means of said other feed means, means adapted to be actuated at the completion of the forward feed of the slide to operate said control means whereby said clutch shifting means is actuated to disengage said clutch means of said other feed means and engage said clutch means of said first feed means, whereby return movement of said slide is effected by said first feed means, means on said first feed means adapted at the end of said return feed movement to move both of said clutch means into neutral position, and means actuated by said slide adapted at the end of a predetermined period to actuate said control means primarily engage said clutch means of said first feed means.

30. In an automatic machine tool of the character described, a work support, a tool slide, rapid and slow feed means independently geared to said slide, independent driving means for said respective feed means, sliding clutches for connecting said respective drive means to said respective feed means, a pivoted clutch shifting lever adapted to engage one of said clutch means and disengage the other, a sliding control member having a cam yieldably engaged with said lever and adapted upon a predetermined movement to shift said lever with a snap action, and means adapted to move said control member at predetermined points in the movement of said slide to effect variable speed feed thereof.

31. In an automatic machine tool of the character described, a work support, a tool slide, rapid and slow feed means independently geared to said slide, independent driving means for said respective feed means, sliding clutches for connecting said respective drive means to said respective feed means, a pivoted clutch shifting lever adapted to engage one of said clutch means and

disengage the other, a sliding control member having a cam yieldably engaged with said lever and adapted upon a predetermined movement to shift said lever with a snap action, and means adapted at a predetermined point in the forward feed of said slide to move said control member to disengage said rapid feed clutch and engage said slow feed clutch, and means adapted to be actuated at the end of said slow feed to move said control member to engage said rapid feed clutch means and disengage said slow feed clutch means, to effect rapid return movement of said slide.

32. In an automatic machine tool of the character described, a work support, a tool slide, rapid and slow feed means independently geared to said slide, independent driving means for said respective feed means, sliding clutches for connecting said respective drive means to said respective feed means, a pivoted clutch shifting lever adapted to engage one of said clutch means and disengage the other, a sliding control member having a cam yieldably engaged with said lever and adapted upon a predetermined movement to shift said lever with a snap action, means adapted at a predetermined point in the forward feed of said slide to move said control member to disengage said rapid clutch means and engage said slow clutch means, means adapted to limit the forward movement of said slide, and means adapted after a predetermined stationary period at the end of said forward movement to move said control member to engage said rapid feed clutch means and disengage said slow feed clutch means to effect rapid return movement of said slide.

33. In an automatic machine tool of the character described, a work support, a tool slide, rapid and slow feed means independently geared to said slide, independent driving means for said respective feed means, sliding clutches for connecting said respective drive means to said respective feed means, a pivoted clutch shifting lever adapted to engage one of said clutch means and disengage the other, a sliding control member having a cam yieldably engaged with said lever and adapted upon a predetermined movement to shift said lever with a snap action, means adapted at a predetermined point in the forward feed of said slide to move said control member to disengage said rapid feed clutch means and engage said slow feed clutch means, means adapted at the end of the forward feed of said slide to partially shift said control member to a point insufficient to shift said lever, means adapted to limit the forward movement of said slide, and means adapted after a predetermined stationary period at the end of said forward feed to complete the movement of said control member to disen-

gage said slow feed clutch and engage said rapid feed clutch to effect rapid return movement of said slide.

34. In an automatic machine tool of the character described, a work support, a tool slide, rapid and slow feed means independently geared to said slide, independent driving means for said respective feed means, sliding clutches for connecting said respective drive means to said rapid and slow feed means, the latter clutch having inclined ratchet teeth, a pivoted clutch shifting lever adapted to engage one of said clutch means and disengage the other, a sliding control member having a cam yieldably engaged with said lever and adapted upon a predetermined movement to shift said lever with a snap action, means adapted at a predetermined point in the forward movement of said slide to move said control member to disengage said rapid feed clutch means and engage said slow feed clutch means, means adapted at the end of said forward movement of the slide to partially shift said control member to a point insufficient to shift said lever, means adapted to limit the forward movement of said slide, said inclined ratchet teeth of said slow feed clutch means adapted after a predetermined stationary period at the end of said forward feed to shift said slow feed clutch means to thereby complete the movement of said control member and engage said rapid feed clutch means, to effect rapid return movement of said slide.
35. In an automatic machine tool of the character described, a work support, a tool slide, independent different speed drive

means geared to said slide, rotary means for manually moving said slide, and lever means actuated by said last named means adapted to move both of said drive means into neutral position during the manual movement of said slide.

36. In an automatic machine tool of the character described, a work support, a tool slide, independent different speed drive means geared to said slide, manually operable means for moving either of said means into operative position or moving both into neutral position, manually operable rotary means adapted to be primarily moved longitudinally to operatively relate it with said slide and secondarily rotated to shift said slide, and lever means actuated by said primary movement adapted to move said first manually operable means into neutral position.

37. In an automatic machine tool of the character described, a work support, a tool slide, a rotary tool in said slide, feed works for moving said slide into and out of relation with the work, means in said feed works adapted to rotate said tool during the traverse of the slide, means actuated at the end of the return feed movement of the slide adapted to stop operation of the feed works for a predetermined period and to automatically start actuation at a predetermined point after said period.

Signed at Bridgeport in the county of Fairfield and State of Connecticut this third day of April A. D., 1924.

EDWARD P. BULLARD, JR.
